NEWSPAPER PRINTING PRESS

Edmund W. Dean, Battle Creek, Mich., assignor
to Duplex Printing Press Company, Battle
Creek, Mich., a corporation of Michigan

Application December 20, 1935, Serial No. 55,465

19 Claims. (Cl. 101—179)

This invention is an improvement in printing presses of the type originally disclosed in Bechman's Patent No. 867,230 dated October 1, 1907, and more particularly as disclosed in my companion application for Newspaper printing presses, filed June 4, 1934, Serial No. 729,013.

The invention disclosed in said application provides a multi-unit press and folder, said press having a plurality of interchangeable printing units and a folder unit or units; which units can be arranged in any desired relation in a line. Any desired number of units may be employed to produce a straight line, straight run, paper or papers of any desired size or number of pages.

Such invention provides a simple and attractive press for newspaper publishers who desire increased production and prefer the single page plate economies and efficiencies and which press will conserve and retain all the advantages of the single so-called "tubular" presses in production and operation, with greatly increased net production speed; and in which any unit may be put into or out of operation as desired.

The object of the present invention is to provide means whereby two plate cylinders are arranged in printing relation to a single blanket cylinder in such manner that if desired the paper may be printed in multi-colors in a single passage through the press; and also to provide means whereby the extra plate cylinders may be put out of operation if it is desired to only print in one color.

Further objects of the invention are to provide novel means whereby the plate cylinders may be independently adjusted relatively to the related impression cylinder, both for producing the impression pressure and also to enable the plate cylinder to be placed out of operative position if it is not desired to use same.

The accompanying drawings illustrate a practical embodiment of my invention, and I will describe the same in detail with reference to said drawings, and summarize in the claims the essentials of the invention and novel combinations and construction of parts for which protection is desired.

In said drawings:—

Fig. 1 is a side elevation of a printing press constructed in accordance with my invention.

Fig. 2 is a vertical transverse section through such unit.

Fig. 3 is an enlarged detail view showing the construction of the respective plate cylinder supporting and adjusting devices.

Fig. 4 is a side view of Fig. 3.

Fig. 5 is a side elevation similar to Fig. 1, showing one multi-color printing cylinder.

Fig. 6 is a vertical transverse section through Fig. 5.

Each printing unit comprises a perfecting printing mechanism with a single or double color attachment, and as shown the perfecting unit consists of cylinders 1 and 1a, and co-acting impression cylinders 2 and 2a. The impression cylinders 2 and 2a are journaled at opposite ends in bearings partly formed in the side frame members 3 and in blocks 3c which are fastened to the members 3 by means of bolts 3d. The plate cylinders 1 and 1a are respectively journaled in annular heads 4a on the lower ends of hangers 4, shown more in detail in Figs. 3 and 4. The hangers 4 are adjustably secured to the outer sides of the journal blocks 3c by means of bolts 4c which pass through slots 4b in the hanger 4 and are tapped into the blocks 3c. The hangers 4 are vertically adjustable so as to regulate the impression pressure contact between the plate cylinder and its related impression cylinder, by means of a supporting screw 4d which is rotatably suspended in a lug 3e on the adjacent block 3c, said screw having a threaded engagement with a socket in the upper end of the hanger 4 (see Figs. 3 and 4). The hanger 4 can be raised or lowered so as to adjust the plate cylinder 1 or 1a as desired relative to its related impression cylinder by first loosening the bolts 4c and then turning hanger bolt 4d. After the cylinder is adjusted it is fastened in adjusted position by tightening bolts 4c.

In the construction shown in Figs. 1 and 2 a multi-color cylinder 1m is located above each impression cylinder and is adapted to cooperate therewith when it is desired to print in multi-color. The cylinder 1m (see Figs. 3 and 4) is mounted in heads on the lower ends of hangers 5 which are hung at their upper ends on pins 5a engaging eye-lugs 6a on vertically adjustable blocks 6. Each block 6 is hung on a rotatable bolt 6b tapped into the upper end of block 6 and hung on an eye 7a attached to an upper frame member 7 mounted upon and secured to the top of member 3.

The members 5 and 6 when properly adjusted vertically may be rigidly clamped in position by a through-bolt 5c which passes through slots in the members 5 and 6 and is tapped into the frame member 7. When it is desired to adjust the cylinder 1m the bolt 5c is loosened, then screw 6b is adjusted to raise or lower cylinder 1m to the

- desired position relative to the periphery of the adjacent impression cylinder 2a; and when properly adjusted the bolt 5c is tightened and securely holds the cylinder in such adjusted position.
- 5 When it is not desired to use either cylinder 1m, the bolt 5c can be loosened, and the hanger 5 swing outward thereby moving the plate cylinder away from the related impression cylinder; and the hanger and cylinder may be held in such 10 non-operative position by adjusting a bolt 5e, tapped in the side of casting 5, until its inner end engages a groove 5f in the bolt 5c.

When bolts 5c are loosened their screw threads force them axially outward allowing the hangers 15 5 to swing outwardly on the pins 5a. The position of the plate cylinder relative to pins 5a is such that it tends to swing outward by gravity when bolts 5c are loosened. Should the force of gravity be insufficient to give the required clearance 20 between the two cylinders the inner ends of the screws 5e contact with the sides of the grooves 5f in the bolts 5c and force the hangers 5 to swing outwardly on the pins 5a, and also prevent the cylinder from swinging back to its 25 former position until the bolts 5c are again tightened. Tightening the bolts 5c forces the hangers 5 against the blocks 6 which are then held against the frames 1.

The cylinder 1m is also adjustable vertically 30 relatively to the impression cylinder 2a by means of the screws 6b (Fig. 3) which are a duplicate of the screws 4a by which the lower cylinder hangers 4d are adjusted.

Each plate cylinder 1, 1a is adapted to carry 35 cylindric plates P, (Figs. 1 and 2) each of which will print one newspaper page of matter. The plates receive ink from suitable inking devices mounted below the cylinder in the side members of the unit frame.

40 Each plate cylinder 1m may also be supplied with ink from an inking mechanism mounted in the frame members 7 above such plate cylinder. As the inking mechanisms form no part of the present invention it is unnecessary to describe the same herein, and they are simply diagrammatically illustrated in the drawings.

Ordinarily the ink for the lower plate cylinders 1 and 1a will be black; and the ink for the upper cylinders 1m would be colored. In the 45 construction shown in Figs. 1 and 2 a sheet could be perfected in black and also in color.

In the construction shown in Figs. 5 and 6 only one multi-color cylinder 1m is shown, and one set of inking mechanism mounted as above described upon a frame member 7x on top the frame 3. The frames 7 and 7x are preferably made interchangeable, so that a frame 7x could be removed and replaced by a frame 7 carrying two cylinders 1m and their inking mechanism, 50 and thus enable the paper to be printed in more colors.

The web can be led through the press in various ways. As indicated in Figs. 1 and 2, the web can be led up over a guide roller 8 and thence 65 between the cylinders 1 and 2, and 1m and 2, thence down between the cylinders 2, 2a; thence between the cylinders 1a and 2a and the cylinders 2a and 1m, to a guide 8a, and thence up over a guide 8b to a folder (not shown). By 70 varying the lead of the web, or using different colored inks in the lower fountains, a large variety of multi-color effects can be produced.

If each printing unit of the press is two plates wide, it will print four pages in multi-color. Six 75 such units would produce 24 pages, the equiv-

alent of a semi-cylindrical sextuple in straight run production. For a 32 page machine two more units would be employed.

Any number of such units may be employed, arranged in line, side by side with the cylinders 5 parallel according to desired capacity of the press, as explained in my aforesaid application.

I claim:—

1. A printing press having side frames, coacting plate and impression cylinders, fixed bearings for the impression cylinder on said frames, bearings for the plate cylinder slidably mounted on the outer edges of the side frames and adjustable in a straight line toward or from the impression cylinder. 10

2. In a printing press as set forth in claim 1, adjustable hangers carrying the bearings for the plate cylinder, means for adjusting the hangers, and separate means for securing the hangers in adjusted position. 15

3. In a printing press as set forth in claim 1, hangers supporting the bearings of the plate cylinder, adjustable blocks to which the hangers are swingably connected, means for adjusting the blocks, and means for fastening the hanger 25 and blocks to secure the cylinder in adjusted position.

4. In mechanism as set forth in claim 1, swingable hangers supporting the plate cylinder bearings, means whereby the hangers may be fastened to hold the cylinder in contact with the impression cylinder, and means whereby the hangers may be held outwardly to keep the plate cylinder out of contact with the impression cylinder. 30

5. A printing press having side frames, impression cylinders mounted on the frames, vertically adjustable hangers carrying bearings for the plate cylinders slidably mounted on the outer edges of the side frames, plate cylinders journaled in said bearings, means for vertically adjusting the said hangers, and means for securing the hangers in adjusted position. 35

6. In a printing press having co-acting plate and impression cylinders, hangers supporting the 40 bearings of the plate cylinders, vertically adjustable blocks to which the hangers are swingably connected, means for vertically adjusting the blocks, and means for positively fastening the hanger and block to hold the cylinder in adjusted 45 position.

7. In a printing press having co-acting plate and impression cylinders, swingable hangers supporting the plate cylinder bearings, means whereby the hangers may be fastened to hold the cylinders in contact with the related impression cylinder, and means whereby the hangers may be held outwardly to keep the plate cylinder out of contact. 55

8. In a multi-color printing press, a frame, an impression cylinder mounted in fixed bearings on said frame, a plate cylinder adapted to cooperate with said impression cylinder, adjustable bearings for the plate cylinder on said frame, a second plate cylinder adapted to cooperate with said impression cylinder, swingable hangers in which said second plate cylinder is journaled, means for adjusting and locking said hangers. 60

9. In a printing press of the character specified having co-acting plate and impression cylinders, the impression cylinders being journaled in fixed bearings, and the plate cylinders being mounted in adjustable bearings attached to the bearing blocks of the impression cylinders where- 70

by they may be independently adjusted relatively to the impression cylinders.

10. In a multi-color printing press, a frame, an impression cylinder, a plate cylinder adapted to cooperate with said impression cylinder, a second plate cylinder adapted to cooperate with said impression cylinder; swingable hangers in which said second plate cylinder is journaled, and means for adjusting said hangers to shift the second plate cylinder an appreciable distance from the impression cylinder and for returning it to its previously adjusted operative position, without disturbing such adjustment.

11. In a multi-color printing press, a frame, an impression cylinder mounted in fixed bearings, a plate cylinder mounted in adjustable bearings adapted to cooperate with said impression cylinder, and a second plate cylinder mounted in adjustable bearings adapted to cooperate with said impression cylinder, swingable hangers in which said second plate cylinder is journaled, vertically adjustable blocks carrying said hangers, and means for shifting the swingable hangers to position the second plate cylinder an appreciable distance from the impression cylinder and for returning it to its previously adjusted operative position without disturbing such adjustment.

12. In a multi-color printing press, a frame, impression cylinders mounted in fixed bearings on said frame, and a plate cylinder coacting with each impression cylinder and mounted in adjustable bearings on said frame; a second plate cylinder cooperating with each impression cylinder, swingable hangers attached to said frame and in which said second plate cylinders are journaled, and vertically adjustable blocks carrying said hangers, and means for adjusting the swingable hangers to position the second plate cylinder an appreciable distance from the impression cylinder and for returning it to its previously adjusted operative position without disturbing such adjustment.

13. A multi-color printing press having a frame, impression cylinders, and a plate cylinder coacting with each impression cylinder; a second plate cylinder beside and cooperating with an impression cylinder, hangers in which said second plate cylinder is journaled, and vertically adjustable blocks carrying said hangers, and means for adjusting said hangers to shift the position of the second plate cylinder an appreciable distance from the impression cylinder and for returning it to its previously adjusted operative position without disturbing such adjustment.

14. A multi-color printing press, a frame, impression cylinders mounted in fixed bearings in said frame, a plate cylinder coacting with each impression cylinder, and vertically adjustable bearings on the frame for each plate cylinder; a second plate cylinder for and cooperating with each impression cylinder, swingable hangers in

which said second plate cylinder is journaled, vertically adjustable blocks carrying said hangers, and means for adjusting the swinging hangers on the blocks.

15. In a multi-color press, a frame, impression cylinders journaled in the frame, a plate cylinder coacting with each impression cylinder, adjustable hangers on the frame supporting the bearings of the said plate cylinders; a second plate cylinder cooperating with each impression cylinder, swingable hangers in which said second plate cylinders are journaled, vertically adjustable blocks carrying said hangers, and means for adjusting and locking the swingable hangers.

16. In a multi-color printing press, a frame, impression cylinders mounted in said frame, a lower plate cylinder coacting with each impression cylinder, adjustable hangers mounted on the frame and supporting the bearings for the lower plate cylinders, an upper plate cylinder cooperating with each impression cylinder, vertically adjustable blocks attached to the side edges of the frame, adjustable swingable hangers attached to said blocks and carrying the bearings for the upper plate cylinders, and means for adjusting and locking the swingable hangers.

17. In a multi-color printing press, a frame, impression cylinders mounted in fixed bearings in said frame, a plate cylinder coacting with each impression cylinder; means for vertically adjusting the plate cylinders relatively to the impression cylinder; a second plate cylinder cooperating with each impression cylinder, swingable hangers carrying the bearings for the second plate cylinder, adjustable blocks mounted on the frame and to which the hangers are pivoted; means for adjusting the blocks on the frame, and means for adjusting and locking the swingable hangers on the blocks.

18. In a multi-color printing press, a frame, impression cylinders mounted in fixed bearings on the frame; lower plate cylinders coacting with the impression cylinders, vertically adjustable hangers supporting the bearings for the lower plate cylinders, upper plate cylinders cooperating with the impression cylinders, vertically adjustable blocks attached to the side edges of the frame and carrying the bearings for the upper plate cylinders mounted on the blocks, and means to adjust the hangers on the blocks.

19. In a multi-color printing press, a frame, impression cylinders, a lower plate cylinder coacting with each impression cylinder, an upper plate cylinder cooperating with each impression cylinder, vertically adjustable members attached to the frame, and hangers carrying the upper plate cylinders and swingably pivoted on said adjustable members, means for adjusting said members on the frame, and means for adjusting and locking the hangers on said members.

EDMUND W. DEAN.
